UNITED STATES PATENT OFFICE.

JOHN O'CONNELL, OF COHOES, NEW YORK.

COTTON-CLEANING APPARATUS.

1,239,432.

Specification of Letters Patent. Patented Sept. 4, 1917.

Application filed March 27, 1917. Serial No. 157,602.

To all whom it may concern:

Be it known that I, JOHN O'CONNELL, a citizen of the United States of America, residing at Cohoes, in the county of Albany 5 and State of New York, have invented certain new and useful Improvements in Cotton-Cleaning Apparatus, of which the following is a specification.

This invention relates generally to machines for cleaning fiber, such as cotton fibers and the like, for example. More particularly, the invention relates to the delivery end of such machines and to the removal of the fibers therefrom.

15 The invention is capable of general application to all machines for cleaning fiber. For example, it may be advantageously embodied in cotton openers, breakers, pickers, and machines of like character. For the 20 purposes of illustration, however, the invention will be disclosed in but one of its specific uses, namely, as applied to a cotton opener.

25 The main object of this invention is to provide in a machine for cleaning cotton and the like automatic means whereby the cotton, while still in loosened condition, may be conveyed from the machine to any desired point, such, for example, as another 30 cleaning machine.

Another object of the invention is to provide in a machine for cleaning cotton and the like a pneumatic means adjacent the delivery exhaust cylinder of the machine, to 35 convey the cotton in loosened condition to another point or to another machine, and means associated with the pneumatic means to permit operation of the latter without neutralizing the suction through said exhaust cylinder.

40 Other objects and advantages will appear in the description to follow and will be particularly pointed out in the appended claims.

45 The invention, in an embodiment at present preferred, is shown for illustrative purposes in the accompanying drawing, in which—

50 The figure shows a sectional elevation of the delivery end of a cotton opener and the feed end of another cotton opener with the improved means for transferring cotton from one to the other.

55 Referring to the drawing in detail, A represents a suitable casing in which the usual parts of a cotton opener are mounted. Only

the delivery end of the opener has been illustrated and for a more complete disclosure of the machine reference is made to my co-pending application Serial No. 157,603 filed 60 March 27, 1917.

The exhaust cylinder 1, of usual construction, is connected by a passage 2 to a suitable source of suction as the fan indicated roughly by 2'. Cotton after having been 65 cleaned is drawn to cylinder 1 and formed in a layer thereon. An arcuate plate 3 adjustably movable closely adjacent the inner periphery of cylinder 1 as indicated is arranged for circular adjustment about the 70 axis of the cylinder to close off any desired portion of its perforated periphery. A rotatable picker wheel 4 is arranged to pick off the cotton from cylinder 1. Sector 3 releases the hold on the lap of cotton on cylinder 1 at 75 the proper time for it to be picked off by wheel 4. Another wheel 5 cooperates with the latter, and the cotton is opened up into finely divided form and thrown up a pipe 6. The point of release of the cotton lap from 80 cylinder 1 may be varied, as desired, and as may be required for different working conditions or different qualities of material. The structure thus far described is well known in the art, and a more complete disclosure may be had by reference to the 85 above-identified copending application.

Reference B represents the casing of another machine located at a distance from the described machine, as, for example, on the floor above that on which the latter is located. This machine may be another cotton opener or any other similar machine for cleaning cotton and the like. The feed end 90 only of this machine has been illustrated, 95 and it may be considered for the purposes of illustration as similar to that disclosed in the above mentioned copending application. Exhaust cylinders 7 and 8 of the usual type are arranged in proper relation for co-operative action to lap the cotton delivered thereto in loosened condition in a manner to be described. The cotton delivered from the 100 exhaust cylinders in lap form passes to and between a pair of feed rolls 9 which, in turn, may deliver the lapped cotton to a beater cylinder or the like. Cylinders 7 and 8 are connected by passages 10 and 11, respectively, to a substantially vertical pipe 12 on the rear side of casing B. The pipe 12 is 105 connected by a pipe 13 to a suitable exhaust fan 14.

110

The described passage 6 is upwardly inclined and intersects a vertically arranged pipe 15. The latter extends to the feed end of casing B having a gradually curving and 5 diverging mouth 16 opening toward and adjacent to the exhaust cylinders 7 and 8. Pipe 15 extends a considerable distance below its point of intersection with pipe 6 and the lower end of pipe 15 has an opening 10 therein which may be controlled by a valve or damper 17. The latter may be held in various positions of adjustment by any suitable means such as the slotted arm 18, for example.

15. The operation of transferring cotton from machine A to machine B will now be described. It will be obvious that fan 14 creates an upward draft in pipe 15, the air entering through the opening near the base 20 of the pipe. The amount of air entering pipe 15 and hence the degree of suction produced therein, is regulable by valve 17. It will be noted that the suction through the exhaust cylinder 1 and pipe 2, operative to 25 hold the cotton fibers to cylinder 1, is opposed to that produced by fan 14. Therefore, the latter cannot be permitted to draw the cotton directly from picker wheels 4 and 5 through passage 6, for the effectiveness 30 of exhaust cylinder 1 would thereby be seriously diminished. By providing an inlet at the base of pipe 15, however, an upward draft is obtained therein which does not impair to any appreciable extent the 35 operation of exhaust cylinder 1. The picker wheel 4 removes the cotton lap from cylinder 1, and by coaction with picker wheel 5, loosens the cotton fibers and throws them up the pipe 6. The revolving wheels 4 and 5 40 exert sufficient force on the fibers to throw them upwardly through pipe 6 into pipe 15, and the fibers are then carried by upward draft to the mouth 16 and thence to the exhaust cylinders 7 and 8. The latter act in 45 the usual and known manner to form the fibers into a lap which is then delivered to feed rolls 9.

Thus the fibers cleaned by one machine may be rapidly and efficiently carried while 50 yet in loosened condition to another machine or to any desired point. Moreover, this result is obtained automatically by means which do not neutralize or impair the effectiveness of the suction from the exhaust cylinder of the delivering machine. The fibers, being relatively light, require but 55 relatively little force to carry them upwardly, and the regulable upward draft is sufficient to accomplish the transfer of the fibers without interference with the operation of the machine delivering the fibers.

The invention has been described in a preferred form for illustrative purposes, but the scope of the invention is defined by the

appended claims rather than by the foregoing description.

What I claim is—

1. Apparatus for cleaning cotton and the like, comprising in combination, a cleaning machine including an exhaust cylinder to 70 collect the cleaned fibers and picker wheels to remove the fibers from said cylinder and to loosen and expel the fibers, a second cleaning machine at a distance from the first machine and suction means to automatically 75 transfer the fibers in loosened condition to the feed end of the second machine, and means to regulate the force of said suction means to prevent neutralization of the suction from said exhaust cylinder. 80

2. In a machine for cleaning cotton and the like, an exhaust cylinder to collect the cleaned fibers, picker wheels to remove the fibers from the cylinder and to loosen and expel the fibers, a passage extending to a 85 predetermined point and into which the fibers are expelled, and means to create a draft in said passage to convey the fibers expelled therein to said point, and means to regulate said draft, all constructed and arranged for the automatic transfer of fibers 90 in loosened condition to a predetermined point without neutralizing the suction from said exhaust cylinder.

3. Apparatus for cleaning cotton and the like, comprising in combination, a cleaning machine including an exhaust cylinder to collect the cleaned fibers and picker wheels to remove the fibers from said cylinder and to loosen and expel the fibers, a second cleaning machine at a distance from the first machine, an exhaust cylinder therein, a passage extending from the latter adjacent to and beyond said picker wheels and into 100 which the fibers may be expelled from the latter, and a regulable opening in said passage at a point beyond the picker wheels, all constructed and arranged for the automatic transfer of the fibers in loosened condition to the exhaust cylinder of the second 110 machine without impairing the effectiveness of the exhaust cylinder of the first machine. 105

4. In a machine for cleaning cotton and the like, an exhaust cylinder to collect the fibers at the delivery end of the machine, picker wheels coöperating with the cylinder to remove the fibers from the latter and to loosen and expel the fibers, a passage extending to a predetermined point and into which the fibers may be expelled at a point 115 intermediate the ends of said passage, means to create a draft in said passage to convey the loosened fibers to said point, and means to regulate the draft constructed and arranged so that the latter is prevented from 120 neutralizing the suction of the exhaust cylinder. 125

5. In a machine for cleaning cotton and

the like, an exhaust cylinder to collect the fibers, picker wheels to remove the fibers from the cylinder and to loosen and expel the fibers, a passage extending to a predetermined point, said passage having a vertical portion into which the fibers are expelled in loosened condition, and means to create a draft in said passage to convey the fibers expelled therein to said point, said vertical portion being arranged for the separation of impurities from the loosened fibers as they pass therethrough. 10

JOHN O'CONNELL.
